(Cl. D12—2)

To all whom it may concern:

Be it known that we, Kenneth George Dumbrell and Geoffrey Noel Dumbrell, citizens of the Commonwealth of Australia, residing, respectively, at Hawthorn, near Melbourne, in the State of Victoria, Commonwealth of Australia, and at Toorak, near Melbourne, in the State of Victoria, Commonwealth of Australia, have invented a new, original, and ornamental Design for an Ear Tag for Sheep and Other Animals, of which the following is a specification, reference being had to the accompanying drawing, forming part thereof.

Fig. 1 is a perspective view of an ear tag for sheep and other animals, showing our new design.

Fig. 2 is a top plan view thereof.

Fig. 3 is a side elevation.

Fig. 4 is a rear end elevation.

Fig. 5 is a front end elevation.

Fig. 6 is a bottom plan view.

Fig. 7 is a side elevation opposite to that of Fig. 3.

We claim:

The ornamental design for an ear tag for sheep and other animals, substantially as shown.

KENNETH GEORGE DUMBRELL.
GEOFFREY NOEL DUMBRELL.
